UNITED STATES PATENT OFFICE.

LUKE J. FAIRBANKS, OF LOS ANGELES, CALIFORNIA.

SAMPLE-DISPENSER.

1,278,450.

Specification of Letters Patent. Patented Sept. 10, 1918.

Application filed July 15, 1916. Serial No. 109,480.

To all whom it may concern:

Be it known that I, LUKE J. FAIRBANKS, a citizen of the United States of America, residing at Los Angeles, in the county of 5 Los Angeles and State of California, have invented new and useful Improvements in Sample-Dispensers, of which the following is a specification.

This invention relates to sample dispensers, and the invention has for its object 10 to provide a dispenser suitable for the use of salesmen, canvassers and the like for the display and dispensing of wares such as display and dispensing of semi-liquids, liquids, olives, and, in fact, all 15 goods of such nature as would otherwise be difficult of display and sampling. The difficulties of displaying the contents of a can of goods to a prospective customer by a canvasser, in attractive manner and without undue waste, are well-known to all 20 grocery salesmen. In ordinary practice a can of a particular brand of goods must be opened so that the contents thereof may be sampled and the goods exposed to view, 25 and no attractive and sanitary way of displaying such goods to a second customer has heretofore been known.

In accordance with the present invention I provide a sample dispenser, container or 30 case adapted to contain goods of the general nature stated suitable for the display of such goods by a salesman without undue waste and without deterioration of the contents of such case or the like. The dispenser preferably consists of a box-like portion 35 provided with a closure adapted to be sealed against such body portion and being hinged thereto, an outstanding ledge or wall portion being provided to prevent the accidental 40 slopping over of the contents of the dispenser when the closure portion is open. Furthermore, latch means are provided to firmly secure the closure to the body or box portion when the container is to be carried.

45 The invention has for a further object to provide an improved dispenser of the general character stated in which utility is combined with attractiveness, which is susceptible of adaptation to a wide range of uses and services, and which will be superior in 50 point of relative simplicity and inexpensiveness of construction and organization combined with effectiveness in operation and use and durability and compactness of form. 55 With the above and other objects in view

the invention consists in the novel provision, formation, association and relative arrangement and inter-relation of parts, members and features, all as hereinafter described, shown in the drawing and finally pointed 60 out in claims:

In the drawing:

Figure 1 is a plan view partly in section of a sample dispenser constructed and organized in accordance with the invention; 65 and,

Fig. 2 is a central vertical sectional view taken on the line x^2-x^2 , Fig. 1, and looking in the direction of the appended arrows.

Corresponding parts in both the figures 70 are designated by the same reference characters.

Referring with particularity to the drawing, in the embodiment of the invention therein shown A designates a box-like member, B designates a closure member, C designates sealing means, and D designates means for latching the closure B to the body A.

The body portion A may be formed of 80 sheet material and preferably comprises end walls 3 and 4, side walls 5 and 6, and a bottom wall 7. The side and end walls are laterally horizontally extended near their tops as at 8 to provide a seat for the closure 85 B and such walls are further angularly upwardly directed as at 9 to provide an upstanding wall extending around the periphery of the member A. Such upstanding wall 9 is finished as by a bead 10.

The closure B is hinged to the peripheral wall 9 as by hinges 11 secured to the peripheral wall 9 as at 12 and secured to the closure B as at 13 and such closure B preferably consists of a plate 14 of proper dimensions to lie upon the laterally extending ledges 8 of the body portion A, it being understood that the sealing means C, which may consist of a gasket of rubber or the like, is interposed between the closure B and the ledges 8. The gasket may be formed with a central opening 15 registering with the interior of the box-like member A.

The latching means B is shown as comprising a three-armed spider 16 of sheet 105 metal, a plurality of cams 17^a, 17^b and 17^c co-acting respectively with the arms 16^a, 16^b and 16^c of the spider 16, and a plurality of notches 18 provided in the peripheral wall 9 of the body portion A for the reception of 110

the spider arms' 16^a, 16^b and 16^c. The spider 16 is preferably centrally pivotally secured to the closure 14 as by a rivet or the like 19, a bushing 20 being interposed between the 5 spider 16 and such closure 14. The cams 17^a, 17^b and 17^c preferably each comprise a wedge-like upstanding wall over which a spider arm is adapted to ride. To provide for greater strength in the closure plate 14 a 10 channel 21 may be provided as by pressing in the metal of such closure lid.

The operation, method of use and advantages of the invention will be readily understood from the foregoing disclosure, taken 15 in connection with the accompanying drawing and the following statement:

The dispenser may be filled with samples of such wares as it is desired to exhibit, such 20 for instance as semi-liquids, and the closure caused to compress the elastic seal C, as by 25 rotating the spider 16 an arm of the same will be forced into each of the notches 18 provided in the peripheral wall 9 and as such arms ride over the cams 17^a, 17^b and 17^c the closure is firmly pressed against the elastic 30 seal and united with the body portion making a leak-proof joint so that the sample case may be carried in any position without fear of leakage or deterioration of the 35 goods due to the introduction or intrusion of air. To exhibit the goods and sample the same it is only necessary to place the dispenser right-side up, rotate the spider in such direction as is necessary to withdraw 40 the arms thereof from the respective notches 18, whereupon the lid may be opened and the dispenser handed to a customer so that the

goods may be inspected and samples withdrawn if desired.

Having thus disclosed my invention I 40 claim and desire to secure by Letters Patent:

1. A sample dispenser comprising a container having its upright walls outwardly and upwardly offset adjacent to their upper edges, a closure hinged to said container and adapted to rest upon the outwardly extending portions of said walls, said upwardly extending offset portion being provided with notches, a holding member rotatably mounted upon the closure and adapted to extend 45 into the notches and a cam member on said closure for engaging and frictionally holding said holding means within the notches.

2. A sample dispenser comprising a container of rectangular outline having its upright walls laterally and outwardly offset and then extending upwardly at their upper edges, a closure hinged along one edge to the container and adapted to seat upon the lateral offset portions of the walls thereof and 60 a holding member rotatably mounted upon the closure and having portions for engagement and coöperation with all of the walls of the container other than the wall to which the closure is hinged and engaging said 65 walls at points intermediate of the ends thereof and holding the closure in place.

In testimony whereof I have signed my name to this specification in the presence of two subscribing witnesses.

LUKE J. FAIRBANKS.
